UNITED STATES PATENT OFFICE.

LESLIE FAWCETT LAMPLOUGH, OF CHICAGO, ILLINOIS, ASSIGNOR TO WESTERN ELECTRIC COMPANY, INCORPORATED, OF NEW YORK, N. Y., A CORPORATION OF NEW YORK.

FEEDING MECHANISM.

Application filed July 31, 1923, Serial No. 654,962. Renewed February 21, 1928.

This invention relates to feeding mechanism, and more particularly to a mechanism for feeding a strand into a container.

In the manufacture of rubber covered wire, where a core of wire is coated with a rubber compound which is later to be vulcanized, it is necessary in the stage before vulcanization to preserve the comparatively plastic coating from distortion, which would 5 deleteriously affect its insulating power. This may be accomplished by coiling the coated strand in superimposed layers, each convolution of which fits smoothly against the adjacent ones, and surrounding and supporting 10 it with powdered soapstone to prevent deformation of the coating and adhesion of adjacent turns.

An object of the present invention is to intermittently deposit a substance into a movable receiver.

Another object is to operate a device for depositing a substance into a reciprocating receiver by the reciprocating action of the receiver.

25 An apparatus made in accordance with the invention may comprise a rotatable storage pan mounted upon a movable carriage which is operated reciprocally at a predetermined speed, and a hopper mounted above the pan 30 and operating with the carriage to intermittently discharge powdered soapstone into the pan.

These and other features of the invention not specifically mentioned will appear from 35 the following description and the accompanying drawings, in which

Fig. 1 is a view in side elevation of a machine embodying the invention;

Fig. 2 is a view in end elevation of the 40 same;

Fig. 3 is a partial plan view of the mechanism showing the pan and hopper;

Fig. 4 shows an enlarged partial section on the line 4—4 of Fig. 1, and

45 Fig. 5 is a fragmentary plan view of the driving mechanism and associated parts.

Referring to the drawings in detail, a base plate 10, which may be of cast metal, has parallel ridges 11 on its upper surface running 50 longitudinally thereof to form a track for a carriage shown generally at 12, which moves reciprocally thereon during the operation of the machine. At either end of this base

plate are affixed uprights 14 and 16 respectively, while a third upright 18 carries a capstan 38 which receives the wire 13 from a covering machine (not shown) and feeds it into the coiling machine. A drive shaft 20 is carried by bearings in upright 16 and 18 and may be operated by a driven pulley 22 keyed 55 to this shaft and rotated by a belt 24 which may be connected to any suitable source of power (not shown) to furnish a variable speed drive therefor. On one end of the drive shaft is affixed a bevel gear 26, which, 60 acting in conjunction with another bevel gear 27, serves to drive a vertical shaft 28, and this in turn through another pair of bevel gears 30 and 32 and a pinion 34 and a rack gear 36, serves to rotate the capstan 38. 65

Also carried by the drive shaft 20 is a member 40 in the form of a truncated cone, which cooperates with a second conical member 42 by means of a belt 44 to drive this second member, and the speed of the second member as to that of the first may be varied by moving the handle 46 connected to a sliding yoke 48 to change the position of the belt 44. The second conical member has integral therewith a bevel gear 50, which, cooperating 70 with a bevel gear 52, drives a shaft 54 supported between uprights 14 and 16. Keyed to this shaft is a wheel 56, upon the hub of which is affixed a sprocket wheel 58. The periphery of the wheel 56 carries a tire 85 23, which may be of rubber, as does also a second wheel 60 integral with a bushing 62 which rides loosely upon the shaft 54 so as to be able to rotate independently thereof. This bushing is machined on one side of the 90 wheel 60 to form a reversible screw thread 64, and annular plates 66, bearing against the ends of the threaded part of the bushing 62, form a thrust bearing therefor, causing the carriage to be moved with the bushing. 95

A post 84, affixed to the bed of the machine, carries in its upper end a dog 86 which fits into the reversible thread of the bushing and is reversed as it reaches either end of the thread in a well-known manner. From the 100 sprocket 58 a drive chain 19 encircles a second sprocket on shaft 68, which is carried by bearings in uprights 14 and 16 and has integral with it two drive clutch members 70, the purpose of which will be made clear later. 105 To consider the carriage 12 in detail, a

support having two end frames 72, each of which is supported on two wheels 74, carries a rotatable disk 76 which is mounted on a ball bearing pivot 78 and rests on the two wheels 56 and 60. A pan 80, which has a circular wall 82 about its center to aid in properly seating wire during the operation of the machine, rests on this table and is held in position by a central tubular portion 17 of the pan 80 which fits over the post 21 integral with the platform 76.

Extending from the rear of the carriage is an arm 90 which carries a hopper 92 in which powdered soapstone may be placed and in which a brush 94 is rotatably mounted over a slot 96 in the bottom of the hopper. A friction drive wheel 98 is rotatably mounted on the lower end of an arm 97, pivoted at 93, the upper end of this arm being held between a screw 89 and a spring 85. A pulley 81, integral with wheel 98, carries a belt 77, which, operating around idlers 73 and pulley 69, transmits the motion of wheel 98 to the shaft of the brush 94. The idlers 73 are mounted on either side of a pivoted weight 65 which acts to keep the belt 77 taut at all times. It will be noted that the pulley 69 is fixed upon an arm from post 90, while the hopper is pivotally mounted upon a sleeve 61 which fits over a post 57 integral with arm 90. A pin 51 set in post 57 and riding in a slot 47 in the sleeve 61, serves to limit the rotation of the sleeve, while a locking pin 41, being forced inwardly by spring 37, fits into a depression in post 57, when the hopper is in position for operation, to lock the sleeve in place. In order to permit the hopper to swing on its pivot, the shaft of the pulley 69 is splined at one end and a projection from the brush shaft fits into it as shown at 33, thus permitting the separation of these parts when the hopper is swung away from the pan, and their union when it is swung back.

The operation of the machine is as follows: A strand of coated wire is brought from a coating machine (not shown), is given a few turns around the capstan 38 and its end is laid in the pan 80, the bottom of which is covered with powdered soapstone to form a seating for the first layer of wire. The carriage 12 should be at either the outer or the inner limit of its movement when starting an operation so as to make the first layer of wire extend clear across the bottom of the pan. The machine is then ready to be operated by starting the mechanism which operates the drive pulley 22. This causes the capstan 38 to revolve and feed wire into the pan, and also, acting through the variable speed drive cones 40 and 42 and bevel gears 50 and 52, causes the pan 80 to be rotated by causing the rotation of the wheel 56. Table 76 resting on the other wheel 60 causes this wheel to rotate also, which, being integral with the bushing 62 carrying the screw

thread 64, causes the carriage to roll back and forth on the base 10 in the manner previously described.

Wheel 56 remains in the same position on the shaft 54 at all times, but wheel 60 moves laterally with the carriage, and it will be noted that when the carriage is at the right-hand limit of its travel, the wheel 56 is acting near the periphery of the table, while at the other limit of its travel the reverse is true. The peripheral speed of wheel 56 is regulated by means of the variable speed cones 40 and 42 so as to be the same as the speed of the coated wire as it leaves the capstan, and a change of the speed of the drive wheel 56 necessarily changes the rate of rotation of the driven wheel 60 and its associated screw 64.

The wheel 60 being driven by the table will be rotated slowly when wheel 56 is near the periphery of the table, and rapidly when it is near its center, since the table is then being swiftly rotated by wheel 56. The result is clear that when the wire is feeding into the pan near its periphery, the pan is operating at a proper speed to receive it and is slowly moved laterally by the action of the dog 86 in the screw thread 64, since the turns are large here and require a comparatively large amount of wire, while when the wire is feeding into the pan near its center, it is still rotating at the proper speed to receive the wire, but has a faster lateral movement which is necessary, since here the turns are small and require a comparatively small amount of wire per turn.

When the carriage reaches either its outer or its inner limit, the wheel 98 rides up on one of the rotating driving members 70, being held in contact therewith by the spring 85, and, acting through the pulley 81 and the belt 77, causes brush 94 to rotate and deposit a quantity of powdered soapstone into the rotating pan, forming a layer of soapstone over each layer of wire as it is completed. As soon as the advance of the carriage moves the wheel 98 off the driving member 70, the brush ceases to rotate until the advance of the carriage brings the wheel 70 into contact with the other driving member, when it is again rotated. The positions of the driving members 70 are adjustable on their shaft by means of set screws 29 to permit regulation of the time at which they shall engage and release wheel 98.

This intermittent deposit of soapstone gives a very desirable seating for the wire and allows operation of the device at a high rate of speed.

What is claimed is:

1. In a machine for handling strand material having a receptacle for receiving the strand material, a rotary support for the receptacle, a chamber for other material, and means for controlling the discharge of the

material from said chamber to said receiving receptacle comprising a control element, the combination therewith of a reciprocating member associated with said receiving receptacle, and means operated by said member for operating said control element.

2. In a machine for handling strand material having a receptacle for receiving the strand material, a rotary support for the receptacle, a chamber for other material, and means for controlling the discharge of the material from said chamber to said receiving receptacle comprising a control element, the combination therewith of a reciprocating member associated with said receiving receptacle, and means operated intermittently by said member for operating said control element.

3. In a machine for handling strand material having a receptacle for receiving the strand material, a rotary support for the receptacle, a chamber for other material, and means for controlling the discharge of the material from said chamber to said receiving receptacle comprising a control element, the combination therewith of a member associated with said receiving receptacle for causing its reciprocation upon its rotation, and means operated intermittently due to the reciprocation of said member for operating said element to discharge material from said chamber upon the strand stored in said receptacle.

4. In a machine for handling strand material having a receptacle for receiving the strand material, a rotary support for the receptacle, a chamber for other material, and means for controlling the discharge of the material from said chamber to said receiving receptacle comprising a control element, the combination therewith of a reciprocating member associated with said receiving receptacle, and a friction driving means controlled by the reciprocal movement of the receptacle for intermittently actuating said control element.

5. In a machine for handling strand material having a receptacle for receiving the strand material, a rotary support for the receptacle, a chamber for other material and means for controlling the discharge of the material from said chamber to said receiving receptacle comprising a rotatable brush

mounted within the chamber, the combination therewith of a reciprocating member associated with said receptacle, and means controlled by the reciprocating member to intermittently rotate the brush to deposit a layer of the material from the chamber upon the strand stored in the receptacle.

6. In a machine for handling strand material having a receptacle for receiving the strand material, a rotary support for the receptacle, a chamber for other material and means for controlling the discharge of the material from said chamber to said receiving receptacle comprising a rotatable brush mounted within the chamber, the combination therewith of a reciprocating member associated with said receptacle, and means controlled by the reciprocating member to provide an intermittent driving connection between the driving mechanism of the receptacle and the brush.

7. In a machine for handling strand material having a receptacle for receiving the strand material, a rotary support for the receptacle, a chamber for other material and means for controlling the discharge of the material from said chamber to said receiving receptacle comprising a rotatable brush mounted within the chamber, the combination therewith of a reciprocating member associated with said receptacle, means controlled by the reciprocating member to intermittently rotate said brush, and means for regulating the time in which the brush will be operated and released by its operating means.

8. In a machine for handling strand material having a receptacle for receiving the strand material, a rotary support for the receptacle, a chamber for other material and means for controlling the discharge of the material from said chamber to said receiving receptacle comprising a control element, the combination therewith of a rotatable member, two elements fixed to said member and spaced apart, and means movable with the receptacle engaging said fixed elements and driven thereby for operating said discharge controlling element.

In witness whereof, I hereunto subscribe my name this 23 day of July A. D., 1923.

LESLIE FAWCETT LAMPLough.
